Primary Examiner — Mimosa De(74) *Attorney, Agent, or Firm* — Brinks Gilson & Lione(57) **CLAIM**

We claim the ornamental design for a curvaceous love seat, as shown and described.

DESCRIPTION

FIG. 1 is a top front perspective view of a curvaceous love seat;

FIG. 2 is a bottom rear perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

Interior surfaces and other portions of the curvaceous love seat not shown in the illustrated drawings form no part of the claimed design.

1 Claim, 7 Drawing Sheets(56)
